UNITED STATES PATENT OFFICE.

EDWARD F. COOKINHAM, OF FRANKFORT, NEW YORK, ASSIGNOR TO ACME ROAD MACHINERY COMPANY, OF FRANKFORT, NEW YORK, A CORPORATION OF NEW YORK.

STONE CRUSHER.

Application filed January 8, 1923. Serial No. 611,276.

My invention relates particularly to stone crushers, and has for its principal object to provide a stone crusher of relatively light and simple construction which may be easily 5 assembled and taken apart, and which when assembled is of the requisite strength and durability to withstand the rough usages to which machines of this class are frequently subjected.

10 The several features of the invention will be clearly understood from the following description and accompanying drawings, in which,

15 Figure 1 is a longitudinal sectional view, partly in elevation, of a stone crusher embodying the features of the invention in their preferred form;

Fig. 2 is a rear elevation of the same; and

20 Fig. 3 is a detail sectional view taken on the line 3—3 of Fig. 2.

The stone crusher illustrated in the drawings is of the type having a stationary crushing member 2 and a cooperating movable crushing member 4. The stationary 25 crushing member 2 comprises a rectangular steel plate which is secured in upright position on a support or header 6 that extends between the sides 8 of the frame of the machine. The movable crushing member 4

30 comprises a steel plate suitably secured on a carrier 10 which is pivotally mounted at its upper end on a shaft 12 having its ends mounted in flanged bearing blocks 13 removably secured to the side frames. The carrier

35 10 is swung back and forth to cause its crushing plate to cooperate with the stationary crushing plate 4, by means of a driving shaft 14 having its ends journaled in bearings in standards 9 and is driven by

40 means of pulleys 16 secured on its ends. The connection between the jaw carrier 10 and the driving shaft 14 comprises an eccentric 18 formed on the shaft that engages an anti-friction roll 20 on the free end of a lever arm

45 22, the roll being held in engagement with the eccentric by means of coiled springs 24 interposed between the end portion of the arm and an abutment rod 26 having its ends secured to the side frames 8. The arm 22 is

50 provided with a hub 28 of substantially the length of the width of the space between the side frames and is secured by a key 29 on a rock shaft 30 having its ends journaled in suitable bearings in the side frames. The

55 arm 22 is connected with the jaw carrier

10 by means of a link 32 in the form of a flat bar having its longitudinal edges suitably seated in sockets in blocks 34 which in turn are removably mounted in sockets in the arm and in a lug projecting from the 60 lower end portion of the jaw carrier. With this construction upon rotation of the driving shaft 14, the lever arm 22 acts to swing the lower end of the jaw carrier 10 back and forth so as to cause the crushing plates 65 2 and 4 to cooperate to crush and expel material placed between them. Except as hereinafter described, the parts above referred to may be and preferably are of a well known construction.

70 In my improved crusher, the support or header 6 is made separate from the side frames 8, and these parts are adapted to be easily assembled and disassembled. As shown, the side frames are made up of steel 75 plates which are detachably secured at their forward ends to the standards 9 by bolts 36, and at their rear ends to the support or header 6. The header 6 consists of a casting having rearwardly projecting side 80 flanges 38 and reenforcing ribs 40 extending between the flanges and spaced apart. The flanges 38 have projecting portions 41 at the top and bottom thereof that are secured to the side plates 8 by short bolts and nuts 85 42 passing through apertures in these parts. The intermediate portion of the header is secured to the side plates 8 by bolts 44 which extend completely across the header and between the reenforcing ribs 40. The bolts 90 44 extend through axial apertures in thimbles or bushings 48 that are mounted in registering apertures in the flanges 38 and the side plates 8. These apertures taper in-

wardly and the bushings 48 have a cor- 95

responding taper so as to closely fit the apertures. The bolts 44 are provided with nuts 50 that engage the outer ends of the bushings so that by tightening the bolts, the

100 bushings may be forced tightly against the walls of the apertures. With this construction it will be apparent that no shearing strain is placed on the bolts 44 during the operation of the crusher; that all of this

105 strain is effectively borne by the bushings 48 which are of large diameter; and that the bolts 44 effectively prevent the side plates from bulging or spreading. The bushings are easily made to fit the apertures, and the bolts 44 pass through the bushings so that 110

it is not necessary to accurately line up the bushings or the apertures in which they are seated, at opposite sides of the header. The header may be easily removed by removing 5 the bolts 42 and 44 and knocking out the bushings 48. Thus a simple, strong, rigid and durable knock-down construction is provided for securing the header and side plates together, so that these parts are capable of 10 resisting the great strain to which they are subjected during the operation of the crusher in as effective a manner as though they were cast together as a unit as heretofore.

These machines are often exposed to dust, 15 dampness and rain for long periods, and it has been found after the machine has been in use for some time that the actuating lever arm 22 is liable to become so rusted or otherwise set to its rock shaft 30 that it is quite 20 impossible to remove these parts without cutting off the ends of the shaft inside of the side frames of the machines, which of course is objectionable. To overcome this difficulty 25 of the prior constructions, the wall of the bore of the lever arm 22 of the machine illustrated in the drawings is provided with a cored out portion or recess 52 extending substantially 180° of its peripheral length and the wall of this cored out portion is 30 provided with a series of longitudinally extending dove-tailed grooves or slots 54, and after the arm is placed on the shaft this cored out portion is filled with Babbitt or other 35 metal having a low fusing point. The cored out portion 52 is so located, as will be apparent from an inspection of Fig. 1 of the drawings, that the remaining portion of the wall of the bore receives substantially all of 40 the strain of the arm on the shaft during the operation of the machine, materially no strain being placed on the babbitted cored out portion of the bore of the arm.

With this construction when it is desired 45 to remove the shaft and arm as is frequently necessary for the purpose of repair or shipment, the babbitt may be melted by means of a torch or other suitable means, which enables the hub of the arm to be knocked rearwardly so as to disengage the unbabbitted 50 rear portion of the wall of its bore from the shaft and loosen the key 29 from its slot, whereupon the shaft may be easily slipped out of its bearings on the side plates 8, and the arm and shaft removed from the machine.

As will be evident to those skilled in the art my invention permits of various modifications without departing from the spirit thereof or the scope of the appended claims.

60 What I claim is:—

1. A stone crusher having, in combination, a stationary crushing member, a support therefor having its longitudinal edges provided with rearwardly projecting flanges, a 65 cooperating crushing member movable with

relation thereto, and means for holding the stationary crushing member in position comprising side plates arranged adjacent to the outer sides of the flanges, respectively, said side plates and flanges having registering apertures that taper inwardly, with the apertures at opposite sides of said member in axial alignment, tapering bushings fitting said registering apertures and provided with axial apertures, and clamping bolts extending through the axial apertures in said bushings and across the back of said stationary member to secure the plates together and to hold said bushings in position. 70

2. A stone crusher having, in combination, 75 a stationary crushing member, a support therefor having its longitudinal edges provided with rearward projections, a cooperating crushing member movable with relation thereto, and means for holding the stationary crushing member in position comprising side plates arranged adjacent to the outer sides of said projections, said side plates and rearward projections having registering apertures that taper inwardly, with the apertures at opposite sides of said member in axial alignment, tapering bushings fitting said registering apertures and provided with axial apertures, clamping bolts extending 80 through the axial apertures in said bushings and across the back of said stationary member, and nuts on the ends of said bolts engaging the outer ends of said bushings. 85

3. A stone crusher having, in combination, 90 a stationary crushing member, a cooperating crushing member movable with relation thereto, means for holding the stationary crushing member in position comprising a support upon which said member is mounted, side plates between which said support extends, said side plates having apertures in axial alignment and the opposite sides of 95 said supports having apertures registering with said apertures, respectively, in said plates, and means for securing said plates together comprising a bushing extending through each pair of registering apertures, said apertures and bushings tapering inwardly, a bolt extending through each pair of opposed bushings, and clamping nuts on 100 the ends of the bolt engaging the ends of the bushings. 105

4. A stone crusher having, in combination, 110 a stationary crushing member, a cooperating crushing member movable with relation thereto, means for holding the stationary crushing member in position comprising a support upon which said member is mounted, side plates between which said support extends, said side plates having apertures in axial alignment, and the opposite sides of 115 said support having apertures registering with said apertures, respectively, in said plates, and means for securing said plates together comprising a bushing extending 120

through each pair of registering apertures, and a bolt extending through said bushings.

5. The combination of two plates arranged side by side and spaced apart, a member interposed between said plates, said plates having apertures in axial alinement, the opposite sides of said member having apertures regis- tering with said apertures, respectively, in said plates, and means for securing said plates together comprising a bushing extending through each pair of registering apertures, and a bolt extending through said bushings.

EDWARD F. COOKINHAM.
